UNITED STATES PATENT OFFICE.

FRANCIS H. RICHARDS, OF HARTFORD, CONNECTICUT.

DESIGN FOR A SCALE-BEAM FOR GRAIN-WEIGHERS.

SPECIFICATION forming part of Design No. 19,833, dated May 6, 1890.

Application filed April 4, 1890. Serial No. 346,615. Term of patent 14 years.

To all whom it may concern:

Be it known that I, FRANCIS H. RICHARDS, a citizen of the United States, residing at Hartford, in the county of Hartford and State 5 of Connecticut, have invented and produced a new and original Design for a Scale-Beam for Grain-Weighers, of which the following is a specification, reference being had to the accompanying drawings, forming part thereof.

10 In the drawings, Figure 1 is a plan or top view of a scale-beam embodying my design. Fig. 2 is an end elevation of the scale-beam. Similar characters designate like parts in each of the figures.

15 The leading feature of my design resides in the shaft portion and the terminal arms of the structure shown in the drawings. The shaft S has at the ends thereof the oppositely-disposed arms B and D, outwardly and down-

wardly curved. Each said arm is furnished 20 with a V-shaped outline or form, which may be set with the apex upward, as shown by solid lines at F, or downward, as shown by dotted lines f, the effect sought to be obtained being the appearance of a sharp angle 25 at those places. On the opposite side of the shaft, and intermediate of the length thereof, there is another arm E. This arm is also furnished with a similar V-shaped form, designated at F' or f'.

30

I claim—

The design for a grain-weigher scale-beam herein shown and described, substantially as set forth.

FRANCIS H. RICHARDS.
